UNITED STATES PATENT OFFICE.

JOHN P. GILSON, OF PORT WASHINGTON, WISCONSIN, ASSIGNOR TO KWIK-MIX CONCRETE MIXER CO., OF PORT WASHINGTON, WISCONSIN.

CONCRETE MIXER.

Application filed May 1, 1926. Serial No. 105,982.

This invention relates to mixers.

Concrete mixers of the type having a rotary or otherwise movable mixing chamber are frequently provided with loading buckets or members which are raised by power means to discharge into the mouth of the tilted mixing vessel. Various means have been attempted for permitting the accurate and easy dumping of the material into the mixing vessel, but these devices have heretofore been relatively complicated and have had a large number of movable parts likely to get out of order.

Objects of this invention are to overcome the defects noted above, and to provide a loading bucket for a concrete mixer which is so constructed that a minimum number of movable parts are employed, and in which a very sturdy construction results.

Further objects are to provide a novel form of concrete mixer which is of the utmost simplicity, which may be easily operated, and in which the parts are so formed that the minimum of friction occurs.

An embodiment of the invention is shown in the accompanying drawings, in which:

Figure 1 is a side elevation of the mixer showing the bucket in its lowered position.

Figure 2 is a fragmentary sectional view on the line 2--2 of Figure 1.

Figure 3 is a sectional view on the line 3--3 of Figure 2.

Referring to the drawings, it will be seen that the mixing vessel is indicated at 1 and is carried in any suitable manner by means of a relatively stationary frame 2, such frame being mounted in any convenient manner as for example, upon the wheels 3 to render the device portable.

The frame is provided with uprights 4 and with a lower diagonal brace 5 and an upper diagonal brace 6. The upper portion of the frame is provided with pulleys or drums 7 which receive the elevating cables 8.

The loading bucket 9 is rigidly attached to a pivotally mounted frame provided with a pair of forwardly extending arms 10. These arms are provided with rollers 11 at their extreme forward ends and the rollers are carried within the arcuate slots or grooves formed in guiding members 12 as shown particularly in Figure 1. These guides 12 are fixed and are rigidly secured to the frame of the machine. For example, the guides may be provided with outwardly projecting

lugs 13 and 14—see Figures 1 and 2—which are riveted or otherwise secured to the uprights 4 and to the lower diagonal braces 5. Thus, the guides are very rigidly and securely attached to the frame of the machine, and are consequently, held in a fixed manner and provide a firm and reliable support for the rollers 11. The guides are closed at their ends, as indicated at 15 and 16 in Figure 1.

In using the device, the charge is deposited in the bucket 9, and the cables are operated to elevate the bucket. The bucket swings about the forward ends of the arms 10, such forward ends being adjacent the forward end of the stationary guides 12 during the initial elevating motion of this bucket. However, when the bucket arrives at a position near the end of its stroke, the arms 10 contact with a transverse angle iron or stop 17 which is rigidly carried by the uprights 4 as shown in Figure 1. This causes the then lower end of the arms 10 to move outwardly along the guide 12 until the ends of the arms, or in reality, the rollers 11, are stopped by the ends 15 of the guides 12 as shown in dotted lines in Figure 1. This causes a quick tilt to the bucket and allows it to rock about a new center so that it will accurately and quickly dump its charge into the mixing vessel.

When the bucket is lowered during the first portion of its downward motion, the forward ends of the arms 10 slide to their initial position adjacent the forward ends of the guides 12, and the bucket is lowered into its position shown in full lines in Figure 1.

It will be seen, therefore, that the bucket swings first about one center and thereafter towards the finish of its stroke quickly swings about another center, thus insuring the quick and accurate dumping of the charge into the mixing vessel.

Although the device has been described primarily as adapted for use as a concrete mixer, it is apparent that it may be used to mix any desired materials.

Although the invention has been described in considerable detail, such description is intended as illustrative rather than limiting as the invention may be variously embodied and as the scope of such invention is to be determined as claimed.

I claim:

2
1. In a mixing machine, the combination of a mixing vessel, a frame supporting said vessel, a loading bucket adapted to discharge material into said mixing vessel and having a pair of forwardly extending arms, a pair of fixed guides for guiding the forward ends of said arms, said arms being permanently operatively connected to said guides in all positions of said bucket from 10 loading position to discharge position, and means for elevating said bucket and drawing it forwardly, whereby said bucket will pivot about one center during its initial elevating motion and will pivot about a rearwardly located center during the last portion of its elevating motion.

2. In a mixing machine, the combination of a mixing vessel, a frame supporting said vessel, a charging bucket having a pair of 20 forwardly extending arms, a pair of fixed guides for guiding the forward ends of said arms and permitting the rearward sliding of said forward ends, means for elevating said bucket, and a stop carried by said frame, said arms being adapted to engage said stop intermediate their ends during the last portion of the elevating motion of said bucket.

3. In a mixing machine, the combination 30 of a frame having a pair of uprights, a transverse stop secured to said uprights, a mixing vessel supported from said frame, a charging bucket for said vessel, a pair of arms secured to said bucket and having forwardly projecting arms, a pair of fixed

guides carried by said frame and receiving and guiding the forward ends of said arms, said guides permitting inward and outward motion of said arms, and an elevating cable for rocking said bucket about the forward ends of said arms, said arms being adapted to strike said stop intermediate their ends to cause the forward ends of said arms to swing rearwardly in said guides, whereby said bucket swings about a forward center during its initial rising movement and swings about a rearward center during its final rising movement.

4. In a mixing machine, the combination of a mixing vessel, a frame supporting said vessel, a charging bucket having a pair of forwardly extending arms, a pair of fixed curved guides extending outwardly and upwardly for guiding the forward ends of said arms and permitting the rearward sliding of the forward ends, means for elevating said bucket, and a stop carried by said frame, said arms being adapted to engage said stop intermediate their ends during the last portion of the elevating motion of 60 said bucket, whereby the forward ends of said arms are given a quick upward motion by the upwardly extending portions of said guides.

In testimony that I claim the foregoing 65 I have hereunto set my hand at Port Washington, in the county of Ozaukee and State of Wisconsin.

JOHN P. GILSON.
